UNITED STATES PATENT OFFICE.

JOSEPH W. STOVER, OF NEWTON, MASSACHUSETTS.

NON-INTERFERING FIRE-ALARM BOX.

SPECIFICATION forming part of Letters Patent No. 253,639, dated February 14, 1882.

Application filed June 9, 1881. (No model.)

To all whom it may concern:

Be it known that I, JOSEPH W. STOVER, of Newton, county of Middlesex, State of Massachusetts, have invented an Improvement in 5 Fire-Alarm Signal-Box, of which the following description, in connection with the accompanying drawings, is a specification.

My invention, relating to a fire-alarm signal-box, has for its object to produce a non-interfering box which, if "pulled in" while another box is in operation, will not itself begin to operate until the completion of the signal being sounded by the box first started, when it will be automatically started and will proceed to 15 ring in its alarm.

The invention is shown embodied in a non-interfering box of that class which, when once started and while in operation, so affects the other boxes that their pull or starting-lever, 20 when operated in the usual manner to start a box, will not cause the mechanism to start, such a box being shown in Letters Patent No. 223,218, dated January 6, 1880, to which reference may be had, and upon which the present 25 invention is intended as an improvement. In the said invention the pull or starting-lever was not positively connected with the stop-arm of the actuating-train of the box; but a block or connecting-piece was normally interposed 30 between the said pull and stopping-arm, so that the movement of the pull by the operator would disengage the said stopping-arm from the train and permit the box to operate. The position of the said block or connecting- 35 piece was controlled by an electro-magnet which was operated by the first impulse from any box in giving a signal to remove the said block or disconnect the starting-lever and stopping-arm, so that a subsequent movement of 40 the said starting-lever would not affect the stopping-arm, and a second box consequently could not be set in movement while another one previously started remained in operation. As soon as the alarm was completely given by 45 the box first started, and it had ceased to operate, the blocks were restored to their normal position, so that any other box could now be started. By this arrangement an operator desiring to start a box while another one is already 50 in operation is obliged to wait until the said operating-box has completed its signal, and

then "pull in" the box from which he desires a signal to be given. In my present invention the said block or connecting device between the pull and starting-lever and the stop-arm 55 of the train is dispensed with, so that the said pull will always operate the said stop-arm whether another box is giving a signal or not, and the armature of the controlling-magnet is provided with a stop which, when the said 60 magnet is in its normal condition, has no effect upon the action of the box, so that the operation of the starting-lever will at once set the box in movement; but when the condition of the magnet has been changed, as it is while an 65 alarm is being sounded, the stop connected with the armature is placed in a position to itself stop and hold the actuating-train of its box, so that if the regular stopping-arm of the 70 said box—hereinafter denominated the "main" stop—is disengaged by the starting-lever the box will not begin to operate until the magnet is restored to its normal condition by the completion of the signal which is being sounded from another box, and with which it is not desired to interfere. The said stop operated by the magnet, which may be called the "secondary" or "non-interfering" stop, takes effect 75 upon a different portion of the train from the main stop, and permits a sufficient movement 80 of the point engaged by the said main stop to prevent the latter from re-engaging if disengaged by the operation of the starting lever, the train then remaining held by the secondary or non-interfering stop, and it is consequently permitted to start when the said secondary stop is disengaged by the change of 85 condition of the magnet following the termination of a signal.

The armature in the box that is operating to 90 sound a signal is mechanically held in its normal position, so that it will not be moved like those of the other boxes upon the change of condition of its magnet to stop the box and prevent the signal from being completed. This 95 is accomplished in the present instance by a flange upon the stop-wheel of the train engaging and holding a finger connected with the armature upon the first movement of the said wheel, before the box has sent the first impulse 100 by which the condition of the controlling magnet is changed. The said flange is provided

with an opening at the point which is opposite the said holding-finger while the said wheel is in its normal position of rest and engaged by the main stopping-arm.

- 5 Figure 1 is a front elevation of a fire-alarm signal-box containing my invention, the parts being in their normal condition as when no signal is being given, portions being broken away to show the mechanism behind; Fig. 2, 10 a detail showing the parts in the position assumed when the pull or starting-lever is operated while a signal is being sounded from another box; Fig. 3, a side elevation of the working parts of the box; Fig. 4, a detail illustrating the mechanical holding device for the secondary stop, and Fig. 5 a modification to be referred to.

The actuating-spring *a* engages in the usual manner the gear *b* on the winding-shaft *b'*, the 20 said gear meshing with a pinion on a shaft carrying the stop-wheel *c*, which in turn drives the brake-wheel *d*, the train ending in the escape-wheel *f*, governed by pallets *g*, and fan or pendulum vibrated thereby in the usual manner, and mounted on a rock-shaft, *h*, these parts being essentially as in the patent hereinbefore referred to, and forming no part of the present invention. The stop-wheel *c* is so proportioned to the pinion driven by it and carrying the 25 brake-wheel *d* that in a single revolution of the said stop-wheel the brake-wheel makes a number of complete revolutions equal to the number of times that it is desired to have the signal repeated—in this instance, four; and the 30 said stop-wheel is provided with a stop-point, *i*, (shown as a pin,) which engages a notch, *2*, in the main stop-arm *j*, pivoted at *3*, and pressed toward the said pin *i* by a spring, *k*, its downward movement being limited by the pin *4* engaged 35 the frame-work. The stop-arm *j* is disengaged from the stop-wheel *c* to permit the train to start and cause the brake-wheel to give the signal by the starting-lever or pull *l*, (shown only in Fig. 3,) it being pivoted at *5*, so that 40 when depressed by the operator, as shown in dotted lines, its end *6* engages the end *7* of the stop-arm *j*, raising it from engagement with the pin *i*. The notched stop-arm *j*, taken in connection with the pin *i*, is denominated the 45 50 "hand-operated stopping device," since it is actuated by the hand of the operator applied to the pull *l*.

An electro-magnet, *L*, placed in the circuit over which the signals are sent, is provided 55 with an armature, *m*, pivoted at *8*, and provided with a retracting-spring, *n*, so adjusted that the armature is normally held up to the poles of its magnet by the electric current, which normally flows through the circuit while no 60 signals are being given. While the signals are being given a weaker current is thrown upon a line by the action of a circuit-changer, which may be operated by a repeater, as mentioned in the patent hereinbefore referred to, 65 the said current not being strong enough to hold the armature up to the poles of the mag-

net, so that it assumes the position shown in Fig. 2.

The armature *m* is provided with a rod, *o*, forming the secondary or non-interfering stop, 70 it being extended down in position to engage a finger, *p*, on the rock-shaft *h* when the armature is back from the poles of its magnet, to thus prevent the vibration of the pallets *g* and lock the train of wheel-work, so that if the 75 starting-lever *j* is depressed by the operator while an alarm is being sounded from another box, and the armature consequently not attracted, the box will not start and cause its signals to interfere with the one being sounded 80 from the box already in operation. The stop-wheel *c* will, however, if the stop-arm *j* is thus raised, turn slightly, owing to the lost motion of the parts between the said stop-wheel and the finger *p*, this movement being sufficient 85 to prevent the arm from again falling into engagement with the pin *i*, it remaining as shown in Fig. 2, and consequently as soon as the finger *p* is released by the stop *o* upon the restoration of the magnet *l* to its normal condition after the alarm that is being sounded 90 from the other box has been completed the train will start to give the new signal without any further movement of the starting-lever *k*. When the armature *m* is attracted the stop *o* 95 is in position to leave the pallets and fan free to vibrate to permit the train to move, and the stop-wheel *c* is provided with a holding device, (shown as a flange, *r*,) to engage a hook or projection, *s*, (see Fig. 4,) upon the stop *o* just 100 after the said wheel begins to move and before the condition of the magnet *l* has been changed, so as to prevent the said stop from falling back into the path of the finger *p* in the box that is giving the alarm when the condition of the 105 magnet is thus changed.

The flange *r* is provided with an opening, 9, which is opposite the hook *s* when the wheel *c* is engaged by the stop-arm *j*, thus leaving the stop *o* free to operate.

The tooth *t* of the brake-wheel *d*, that lies in contact with the circuit-springs *u* when the train is stopped in its normal condition, is made slightly broader at its top than the other teeth, so that the said circuit-springs will not be disengaged in the slight movement that takes place when the starting-lever is operated with the stop *o* in position to engage the finger *p*.

It is obvious that the armature *n* may be polarized and the non-interfering stop *o* controlled by the reversal or change of polarity of the current, as described in the patent hereinbefore referred to, and shown in Fig. 5, instead of the change of strength of the said current, as herein described; or any other change in condition of the magnet causing a movement of the armature may be availed of to insure non-interference without departing from the principle of this invention.

I claim—

1. The actuating-train and its hand-operated

main stopping device, combined with the secondary or non-interfering stop for the said train and controlling electro-magnet therefor, arranged and to operate substantially as and for the purpose described.

2. The actuating-train and hand-operated main stopping device therefor, combined with the secondary stop, properly located to engage a different portion of the said train from the 10 said main stopping device, and the controlling electro-magnet for the said secondary stop, substantially as and for the purpose described.

3. The actuating-train and its hand-operated main stopping device, and the secondary stopping device therefor and its controlling electro-magnet, combined with the holding device for the said secondary stopping device, substantially as and for the purpose described.

4. The actuating-train, including the stop-wheel and escapement, and the stop-engaging arm connected with the latter, combined with the main stop-arm and starting-lever therefor,

and the electro-magnet, its armature, and stop-rod connected therewith, substantially as and for the purpose described.

25

5. In a non-interfering signal-box, the actuating-train, combined with the electro-magnet, its armature, and the non-interfering stopping device for the said train operated by the said armature, substantially as and for the purpose 30 described.

6. The actuating-train and electro-magnet and its armature, provided with a stopping device for the said train, and the hooked finger connected with the said stopping device, combined with the train-wheel and its notched holding-flange, substantially as described.

In testimony whereof I have signed my name to this specification in the presence of two subscribing witnesses.
